ELECTRIC SWITCH WITH TIME CONTROL MECHANISM

William F. Edwards, West Hartford, and Johannes R. Carlson, Hartford, Conn., assignors to The Arrow-Hart & Hegeman Electric Company, Hartford, Conn., a corporation of Connecticut

Application January 7, 1939, Serial No. 249,814

8 Claims. (Cl. 200—38)

This invention relates to electric switches for controlling plural circuit arrangements such as for example in electric ranges and the like. More particularly the invention relates to a switch for multiple circuit control which is provided with means to automatically change the circuit connections after the passage of a predetermined time interval.

It is an object of our invention to provide a multiposition rotary electric switch for controlling multiple electric circuits which will be capable of changing the circuit connections after a selected time interval, and which may be manually moved at any time to any one of a plurality of circuit-making positions.

Another object of our invention is to provide a cam-operated type of rotary switch for use with electric range circuits and the like which may be operated by a time control mechanism after a selected time interval and which permits quick separation of the electric contacts at the instant of circuit interruption.

Another object of our invention is to provide a switch of the above type which may have the time control mechanism assembled therein as a separate unit.

Other objects and advantages of our invention will become apparent as the invention is described in connection with the accompanying drawings.

In the drawings:

Figure 1 is a plan view of an electric switch embodying the principles of our invention;

Figure 2 is an elevation view partly in vertical section of the switch in Figure 1;

Figure 3 is a fragmentary detail view of the connection between the switch spindle and the time control mechanism of the invention;

Figure 4 is a view looking into the bottom of the switch in Figure 1 with the time control mechanism removed;

Figure 5 is a plan view of the time control mechanism as removed from the switch in Figure 4;

Figure 6 is a view similar to Figure 4, but with the parts in the position they occupy when the switch is set for a 20-minute time interval;

Figure 7 is a view similar to Figure 5, but with the time mechanism in position corresponding to Figure 6;

Figure 8 is a fragmentary detail view showing in plan one of the line terminals and its associated switch contacts and their cooperation with the operating cam switch spindle.

Figure 9 illustrates in plan another of the line terminals and its associated movable contact.

Referring to the drawings, the switch comprises a two-part casing of molded insulating material in which the switch parts are housed. Preferably, the casing will have plane side and

top walls and will have the operating parts mounted upon the base 2 over which the hollow, cup-like cover 1 fits to enclose and protect the switch parts. Conveniently, the base 2 may be 5 hollowed out from the bottom to receive a clock-work mechanism 70 as hereinafter described.

The switch is operated by a dial handle 3 affixed upon a spindle 4 which extends through the cover 1 and has mounted thereon four cams, such as 35 and 25. These cams are loosely 10 mounted upon but are required to move with the switch spindle by mounting means of the type described in the copending application of Louis A. Yeske, Serial No. 140,705, entitled "Rotary switch," now Patent 2,182,715, dated December 5, 1939. But the present construction

differs from the Yeske invention in the respect that the cams are permitted lost motion relative to the spindle. Briefly, the movement of 15 the cams with the spindle is compelled by the engagement therewith of a member 6 which is keyed to and moves as a unit with the spindle 4 and has arms 6a extending parallel to the spindle through apertures, for example 35a, in the cams. 20 Preferably, the apertures are larger than the cross section of the member 6a, so that the cams are permitted a small amount of movement relative to the spindle and the operating member 6 for a purpose to be hereinafter more fully described. The cams may be spaced by washers, 25 for example 36, 38, affixed to the spindle. If desired the cams and their securing member and spacing washers may be secured in assembled position by peaning over the ends of the securing member under the bottom cam, or they may be secured by a separate anchor disc keyed to the spindle below the bottom cam as in the Yeske invention.

The switch is provided with three line terminals 10, 20, and 30 which have attached to 30 upstanding arms thereof similar spring contact fingers each of which has on its free end a contact button, that is, spring fingers 32 and 33 are mounted upon arms bent up from the sides of the terminal 30 and have contact buttons 31 and 34 mounted on their free ends, respectively. In like manner, the spring finger 11 is mounted upon 35 an upstanding arm (not visible) of the terminal 10 and has a contact button 12 while spring finger 22 is mounted upon an arm (not visible) of the terminal 20 and has a contact button 21. The switch is also provided with load terminals 40, 50 and 60 which have mounted upon 40 upstanding legs thereof button contacts 41, 42, 51 and 64 as indicated, the terminal 40 having two legs and two contacts 41, 42. Upon operation of the switch, the contact 31 engages and disengages the stationary contact 41 as the cam 35 rotates. Contact 34 engages and disengages the stationary contact 64 as the cam 25 rotates. In

55

like manner, the movable contact button 11 engages and disengages the stationary contact 42 and the movable contact button 21 engages and disengages the fixed contact 51 as their respective cams (not visible) are rotated by the switch spindle. In view of the complete disclosure of this type of cam-and-spring switch mechanism in the previously mentioned application of Louis A. Yeske, a further illustration and description of this mechanism will not be necessary. It will be understood by those skilled in the art that by making appropriate wire connections between the line and load terminals and a suitable resistance unit, various degrees of heat, such as high, medium and low heats, may be obtained as the switch is manipulated. It will be understood, however, that the switch is not limited to use with a resistance unit.

For the purpose of controlling the movement of the switch spindle and movable contacts a conventional time control mechanism or clock-work designated generally by the numeral 10 may be secured in the bottom of the switch casing. The clockwork of this mechanism may be of any suitable type or construction, it only being necessary to have the clock mechanism proportioned so as to rotate its main arbor 72 the required amount within a specified period so as to impart a sufficient rotation to the switch spindle 4 to cause operation of the switch contacts at the end of the predetermined interval as hereinafter described.

In order that the motion of the clock mechanism may be imparted to the switch spindle 4 and in order that the manual movement of the switch spindle may be imparted to the clock mechanism for the purpose of winding the same, a disc 13 with a notch 14 therein may be mounted upon an end of the clock arbor 72 which extends toward the switch mechanism and is coaxial with the switch spindle. For engaging with the disc 13 a disc 80 may be rigidly attached to the end of the switch spindle adjacent the disc 13 and may have a projection 81 extending from the face of the disc parallel to the spindle 4 in position to engage in the notch 14, so that the switch spindle 4 and the clock arbor 72 will move as a unit. Preferably, the clock mechanism will be of the type in which rotation of the arbor in one direction will wind the clock spring and set the mechanism for a predetermined period, and which will permit the reversal of the arbor to unwind the spring and nullify or vary the previous setting, when it is desired to do so manually.

To this end a spring clutch disc 90 may be fixed for movement with the clock arbor and may press upon a driving gear 92 of the clock mechanism in conventional fashion so as to move with the gear as the clock mechanism unwinds normally. When the handle is reversed, manually, to nullify a previous clock setting, the disc 90 will slip on the face of the gear 92.

In order that the switch contacts may be held in their various positions, a radial projection 82 is provided upon the disc 80, which projection engages with an indexing spring 84 which may be stamped from resilient sheet metal with a central V-shaped indentation 86 having shoulders 85 and 87 adjacent thereto. Preferably, the indexing spring will be seated in a recess countersunk as at 89 in the underside of the base 2. When moved into the "off" position (Figure 4), the switch will remain there by reason of the engagement of the projection 82 with the shoulder 85 and with a nub 88 on the bottom of the switch

casing extending into the countersunk recess 89. When the switch is in "medium" position the projection 82 will have moved about 45° counter-clockwise from the Figure 4 position, to engage 6 in the indentation 86; and when the switch is in the "low" position the projection 82 will have moved about 45° more in counter-clockwise direction. In that position the clockwork which is under a slight initial tension will hold the projection 82 as against the shoulder 87. Movement of the switch about 135° counter-clockwise from Figure 4 will place it in "high" heat position. While in "high" position it will be at all times under the effort of the clock mechanism and will 15 remain in the "high" heat position only so long as the time interval at which the clock mechanism has been set has not elapsed.

As previously described, the operating member 6 loosely engages the operating cams by reason 20 of the large size apertures 35a, thereby providing lost motion between the operating cams and the member 6. This lost motion permits the pressure of the contact springs, as the cam engaging portions (32c for example) start to move down into the depressed parts 35d of the cam, to move the cams relatively to their operator 6. Thus, the contact springs may snap the contact 25 buttons which they carry away from the corresponding stationary contact buttons as the switch is moved automatically into "low" heat position by the clock mechanism. If this lost motion means were not provided the separation of the contacts automatically would be very slow and would be accompanied by considerable arcing.

In operation the switch may be moved manually into any position by rotation of the dial handle 3. It will remain in either "off," "medium" or "low" positions permanently, that is, until manually moved into another position. The indexing spring prevents the clock mechanism from moving the switch from any of those 40 positions. But, on movement into "high" heat position, the handle is turned until the pointer 45 (Figure 1) indicates the time interval that it is desired to have the switch remain in "high" heat position. When such interval elapses the operating cams will move into "low" position. Just as they do so, the lost motion between them 50 and their operator 6 will allow the contacts and cams to move independently of the operator 6 so as to permit the contacts to snap into their "low" position.

If it is desired to change the setting of the 55 switch after it has once been set for a certain time interval this may be done by manipulating the handle, which will either wind the clock further or unwind it, depending on the direction in which the handle is turned.

From the foregoing, it will be seen that we 60 have provided a novel construction of switch mechanism which is particularly adapted for use in rotary heater switches for the purpose of controlling automatically the movement of the switch from "high" heat or other position into a "low" heat or other position when the time interval for which the switch has been set has 65 elapsed. Also our invention may be assembled in a simple and expeditious manner by incorporating the clock mechanism in the combination after the switch itself has been fully assembled. By reason of our construction, repair, replacement or cleaning of the clock mechanism may be 70 easily and quickly accomplished, or switch parts 75 may be replaced without disassembling the parts

which make up the clock mechanism. We have also provided means for permitting the contacts to snap into "low" heat position as the end of the interval of high heat is reached.

Obviously the terms "high," "medium" and "low" heat positions are simply relative and are used for convenience in designating different positions of a switch which is adaptable generally to multiple circuit control. The invention may be adapted for use in moving the contacts either into or out of any desired switch position. Such adaptations and many modifications within the scope of our invention will occur to those skilled in the art. Therefore, we do not limit the invention to the specific embodiment described.

1. In a manually and automatically operable switch, a plurality of separable switch contacts connectible in at least two different closed-circuit positions and an open-circuit position, manually rotatable means movable in both clockwise and counterclockwise directions, rotary cam means for causing engagement and disengagement of said contacts at will into all of said positions, and a lost-motion connection between said manual means and said cam means, and means settable by rotation of said manual means for moving said contacts at the end of a selected time interval from one of said positions to another position with a snap action.

2. In a manually and automatically operable switch, a plurality of separable switch contacts connectible in at least two different closed-circuit positions and an open-circuit position, manually controllable cam-operating means including a lost-motion connection for causing engagement and disengagement of said contacts at will into all of said positions, and means settable to move said contacts at the end of a selected time interval from one of said positions to another position with a snap action, a separable connection between said settable means and said cam-operating means whereby said settable means may be assembled and removed as a unit from the switch.

3. In a manually and automatically operable switch, a plurality of separable switch contacts connectible in at least two different closed-circuit positions and an open-circuit position, manually operable means to cause engagement and disengagement of said contacts at will into all of said positions, a lost-motion connection between said operating means and said contacts, and means settable to move said contacts at the end of a selected time interval from one of said positions to another position with a snap action, a separable connection between said manually operable means and said settable means whereby said settable means may be assembled and removed as a unit from the switch.

4. In a manually and automatically operable switch, a plurality of separable switch contacts connectible in at least two different closed-circuit positions and an open-circuit position, manually operable means to cause engagement and disengagement of said contacts at will into all of said positions, and means settable to operate said contacts at the end of a selected time interval from one of said positions to another, a separable connection between said manually operable means and said settable means whereby said settable means may be assembled and removed as a unit from the switch.

5. In a rotary switch, an operating shaft, a plurality of separable switch contacts connectible in at least two different closed-circuit positions and an open circuit position, retarded-action means settable for selected time intervals for operating said shaft, cam means operated by said shaft for moving said contacts into one switch position from another, a lost-motion connection between said cam means and said shaft whereby contact operation occurs with a snap-action at the end of the selected time interval, and manual means for operating said shaft in both clockwise and counterclockwise directions to move said contacts into at least two closed-circuit positions and an open-circuit position at any time.

6. In a rotary switch, an operating shaft, a plurality of separable switch contacts connectible in at least two different closed-circuit positions and an open circuit position, retarded-action means settable for selected time intervals for operating said shaft, cam means operated by said shaft for moving said contacts into one switch position from another, a lost-motion connection between said cam means and said shaft whereby contact operation occurs with a snap-action at the end of the selected time interval, and manual means for operating said shaft in both clockwise and counterclockwise directions to move said contacts into at least two closed-circuit positions and an open-circuit position at any time, and to set said retarded means.

7. In a rotary switch, an operating shaft, a plurality of separable switch contacts connectible in at least two different closed-circuit positions and an open circuit position, retarded-action means settable for selected time intervals for operating said shaft, cam means operated by said shaft for moving said contacts into one switch position from another, a lost-motion connection between said cam means and said shaft whereby contact operation occurs with a snap-action at the end of the selected time interval, and manual means for operating said shaft to move said contacts into at least two closed-circuit positions and an open-circuit position at any time, and to set said retarded means, said retarded means being constructed and arranged to be deenergized when said manual means is actuated in one direction to move said contacts from the position in which the retarded means is operating upon them.

8. In a rotary switch, a plurality of separable switch contacts connectible in at least two different closed-circuit positions and an open circuit position, an operating shaft, manually controllable means for operating said shaft, retarded-action means in which energy is stored by rotation of said shaft, said retarded-action means being settable for selected time intervals for operating said shaft, cam means operated by said shaft for controlling contact separation and engagement, and a lost-motion connection between said cam means and said shaft whereby contact operation occurs with a snap-action at the end of the selected time interval, and a separable connection between said retarding means and said shaft permitting assembly and removal of said retarding means as a unit in and from the switch.
